SAMUEL McDONALD, OF CINCINNATI, OHIO.

Letters Patent No. 67,442, dated August 6, 1867.

IMPROVED BED-BOTTOM.

The Schedule referred to in these Letters Patent and making part of the same.

TO WHOM IT MAY CONCERN:

Be it known that I, SAMUEL McDONALD, of Cincinnati, Hamilton county, Ohio, have invented a new and useful Bed-Bottom; and I hereby declare the following to be a full, clear, and exact description thereof, reference being had to the accompanying drawings, making part of this specification.

The object of this invention is a cheap and durable spring-bed bottom, of easy application to any ordinary bedstead, and which admits of shipment in small compass and in few parts. In the accompanying drawings—

Figure 1 shows part of a bedstead with my spring bottom attached.

Figure 2 shows the rubber loop with a section of a cleat cut through at the gain.

Figure 3 shows a modification, in which a rubber cord takes the place of the wood cleats in fig. 1.

A A are the posts, and B B' the head and side rails of a bedstead. To the rails are attached cleats C, which may be of wood or metal, or other suitable substances. In gains D, in the cleats, rubber loops E suspend bearing-rods F. The bearing-rods F support the longitudinal slats G, which slats are supported in one or more places between the ends by transverse slat or slats H, which transverse slats are supported by their appropriate rods F, and have appropriate gains to receive the slats G. In fig. 3 is seen a cord, I, of India rubber, stapled, i., to the rails to form elastic cleats, in place of the wood or metal cleats C.

It will be seen that my improvement may be applied to any common bedstead with but a slight expenditure, and without damaging it in any way.

I claim herein as new and of my invention—

The supporting-rods F and elastic loops E, sustained by either a firm or a yielding attachment to the bedstead, and operating substantially in the manner and for the purpose set forth.

In testimony of which invention I hereunto set my hand.

SAMUEL McDONALD.
